PLANING MACHINE

John Edwin Malam, Birmingham, England, assignor to Imperial Chemical Industries Limited, a corporation of Great Britain

Application September 9, 1935, Serial No. 39,846
In Great Britain November 23, 1934

17 Claims. (CL. 90—38)

This invention relates to the scraping, planing, milling, cleaning or like treatment, of metal or other surfaces and to new and improved apparatus for carrying out such operations. The invention relates in particular to a method and apparatus for preparing the surface of metal sheets, plates or strips prior to cold rolling operations.

The surface of hot rolled metal plates, sheets or strips, especially if such sheets are made of non-ferrous metal such as brass or copper, frequently has to be scraped or otherwise cleaned prior to or at some intermediate stage of the rolling process in order to ensure that the surface of the finished sheet is bright, smooth, and free from surface defects. These scraping or cleaning operations are sometimes carried out by means of hand tools but are then tedious and slow and involve high labour costs. While it is known to clean thick metal sheets or slabs prior to cold rolling by grinding or machining the surface, it has not hitherto been known to remove from the material a very shallow surface layer of uniform thickness, e. g. a uniform layer of less than five thousandths of an inch, unless the surface being treated is absolutely flat. The difficulties in removing such a thin uniform layer are much enhanced when the thickness of the rolled sheet or strip is less than, for example, one fifth of an inch and when the strip does not lie flat on the machine bed and cannot readily be flattened. It has been proposed to clean metal sheets prior to cold rolling by passing them through a form of press in contact with canvas or like cleaning material. This method of cleaning has not been found to be entirely satisfactory since surface blemishes are not completely removed.

The object of my invention is to provide an improved method and apparatus for scraping, planing, milling or cleaning, which will be free from the objections referred to and which will be capable of treating the surface of sheet metal or other material in a rapid and effective manner. A further object of my invention is to provide improved apparatus of this kind in which a minimum amount of material is removed from the sheet consistent with the required degree of cleaning.

According to the present invention, sheet, plate or strip material is treated for the removal of a surface layer of substantially uniform thickness by controlling the "depth" of the cutting or other operating device in accordance with the surface contour of the material being treated.

The term "depth" as applied to the operating device is employed to denote the location of the device in relation to the machine bed or other standard of reference independent of the surface being treated. Thus, according to the invention, if the surface of the strip is not perfectly flat, the cutting edge of the tool is automatically raised or lowered to follow the surface contour of the sheet so that the depth of cut or thickness of the layer removed is substantially constant.

The machines within the invention take various forms but all embody a tool of a suitable sort for removing a surface layer of small thickness from the non-plane strip material to be surfaced and also embody a roller or other suitable support contacting the surface of the said material at a point abreast of and substantially in alignment with the cutting edge of the tool, said roller or equivalent support being rigidly mounted relative to the tool so as to be movable up and down together as they are carried along in the operation of the machine over the strip material and pressed down into engagement therewith, or, alternatively, when the strip material is moved longitudinally relative to the tool. If the contact of the roller with the surface of the material is not abreast of and substantially in alignment with the cutting edge of the tool, the machine is not operative to surface thin undulating or buckled metal sheets which is the object of this invention. Thus if the roller contacts the sheet substantially behind the cutting edge of the tool, the tool tends to dig into any ridge or ripple extending across the strip before the roller can contact with it to raise the tool and consequently uniform depth of cut is not obtained.

Moreover, when the roller rides over the ridge it lifts the tool completely clear of the surface of the sheet in front of the ridge, resulting in an untreated patch. Furthermore, equally unsatisfactory results are obtained if the roller contacts with the sheet substantially in front of the cutting edge of the tool, since in this case the tool is lifted clear of the surface of the sheet as the roller contacts with the ridge, but when the roller rides down the ridge the tool tends to dig into the crest of the said ridge. The net result in both cases will be a surface having a series of relatively deeply cut portions and also a series of untreated patches. Also serious chatter of the tools results when the roller is not located substantially in line with the cutting edge of the tool. A further serious drawback to

the surface treatment of thin sheets where the roller is located substantially behind the cutting edge of the tool is that the downward pressure on the roller tends to throw up a ripple immediately in front of the knife if the sheet does not lie quite flat on the table, and this causes serious chatter of the tool and its supporting means.

All these difficulties are overcome in the present invention by positioning the cutting edge of the tools abreast of and substantially in line with the contact of the roller with the surface of the strip. With such an arrangement the tool or tools are enabled to follow accurately the contour of the strip so that a uniform depth of cut is obtained. Moreover, when treating very thin strips, the pressure on the roller cannot throw up any ripples on buckled parts since its effect is to flatten the thin sheet where the tool or tools contact with the surface so that the ripples due to bending of the sheet itself are to a certain extent flattened out.

There are many materials in sheet, plate, or strip form which can be surfaced in this manner, such as metals consisting of copper or copper alloys, nickel and nickel alloys, iron and steel, aluminium and aluminium alloys, or zinc and its alloys. The surface of non-metallic sheets composed of hard rubber compounds, e. g. ebonite, or plastic materials such as those comprising synthetic resins or cellulose derivatives, may also be treated in a like manner.

According to one form of my invention the apparatus comprises a rigidly supported metal table about four feet wide and seventy feet long which carries a travelling carriage adapted to move along the whole length of the table. A strip of hot rolled brass about two feet wide by one tenth of an inch thick and about sixty feet long, the surface of which is required to be prepared, is placed on top of the table and is firmly secured to same at each end by means of clamps. The travelling carriage may be mounted on two sets of rollers located at the front and rear of the carriage frame and is arranged to ride on top of the brass strip with the rollers in contact with the upper surface of the said strip. One or more sets of cutting or scraping tools are attached to the carriage and these are preferably located in suitable tool holders on either side of the rear rollers. If desired, a series of cutting or scraping tools may be arranged in staggered formation so that a relatively wide strip is treated in one operation without leaving ridges between adjacent series of tools.

The carriage is heavily loaded, preferably by means of a dead weight, so that a distribution of forces ensuring the best conditions for cutting is obtained. Means are provided for traversing the carriage along the whole length of the strip and this may take the form of an endless rope drive which may be driven by means of a suitable winch and electric motor. Alternatively, the carriage may be traversed along the length of the strip by means of an electric motor mounted on the carriage which drives, through suitable gearing, a pinion engaging with a rack affixed to the table. When the carriage is moved forward for the working stroke the cutters engage with the sheet and are set so as to remove a shaving of metal about one and a half thousandths of an inch in thickness. The thickness of the metal removed is maintained substantially uniform throughout the length of the travel, since the tools which are mounted on

the carriage follow the surface contour of the sheet.

In order to prevent the wear of the tools during the backward travel of the carriage, the latter is arranged to be lifted completely clear of the metal strip by means of a further set of rollers mounted on the carriage which are adapted to ride on elevated rails attached to the side frames of the table. The arrangement is such that these rollers are out of contact with the rails during the working travel of the carriage but come into operation automatically to lift the carriage clear of the strip on the backward travel. Other means may also be provided for lifting the tools clear of the work during the return stroke so as to enable a second set of tools to come into operation during that stroke, thus making the device double acting. The tool holders for the tools may be fitted to an automatic cross traversing device whereby the tools are moved in progressive steps across the width of the strip so that the whole surface is finally prepared. Alternatively, the strip itself may be moved laterally across the table, in which case the tool holders are not moved across the carriage. The tools are arranged so as to present themselves to the work at a small cutting angle and the cutting edges may be set obliquely so that the metal shavings are deflected away from the rollers supporting the rear of the carriage.

By this novel method slow and laborious hand scraping operations are eliminated and in addition to greatly speeding up the rate of production, very considerable savings in labour costs are effected thereby.

The invention will now be described with reference to the accompanying drawings which show two methods of carrying same into effect.

In the drawings, Figure 1 is a longitudinal elevation of an improved machine for preparing the surface of metal sheets in which the cutting tools are mounted on a travelling carriage.

Figure 2 is a plan of the machine shown in Figure 1.

Figure 3 is a cross sectional elevation on the line A—A of Figure 2, drawn to a larger scale.

Figure 4 is a side elevation to a larger scale of the travelling carriage of Figure 1.

Figure 5 is a plan view of the travelling carriage shown in Figure 4.

Figure 6 is a part sectional perspective detail of the mechanism for holding the cutting tools of the machine shown in Figure 1.

Figure 7 is a part sectional perspective detail of the mechanism for clamping the metal sheet of the machine shown in Figure 1.

Figure 8 is a longitudinal elevation of an alternative form of machine for preparing the surface of metal sheets in which the cutting tools are mounted on a stationary carriage.

Figure 9 is a plan view of the machine shown in Figure 8.

Figure 10 is a part sectional perspective detail of the lower portion of the mechanism for holding the cutting tools of the machine shown in Figure 8 with some of the component parts separated to illustrate more clearly their configuration.

Fig. 11 is a longitudinal elevation of another form of machine within my invention;

Fig. 12 is a plan view of the machine shown in Fig. 11;

Fig. 13 is a side elevation on a larger scale of the traveling carriage shown in Fig. 11;

Fig. 14 is a plan view of said carriage; and

Fig. 15 is a cross-sectional elevation through the supporting table of the machine showing said carriage in end elevation.

Referring to Figures 1 to 7 of the drawings, the numeral 1 denotes a rigidly supported metal table about four feet wide by seventy feet long which is built up of cast iron sections having a cross section as shown in Figure 3. The sections are carefully levelled and are bolted together so that the whole of the top portion 2 of the table is perfectly flat. Hot rolled brass strips 3, each about two feet wide by about sixty feet long and about one fifth of an inch in thickness are stacked at the side of the machine and the top sheet of the stack is transferred to the table over a number of rollers 4 which are carried in bearer frames 5 arranged at intervals as shown in Figure 2.

Each bearer frame 5 is connected by links 6 to a shaft 7 extending the whole length of the table, and this shaft is rotated to lower one end of all the bearer frames simultaneously to a convenient position to suit any particular height of the stack of strips. The shaft 7 is operated by means of a hand wheel 8 located at one end of the machine, the said hand wheel being adapted to rotate a screwed spindle 9 which engages with a block 10 adapted to slide within a slotted guide in a lever 11 which is keyed to the shaft 7.

The strip 3 is firmly secured in position on the surface of the table by means of clamps which firmly grip the ends of the strip. Three clamps 12 are provided at one end of the table and these are fixed in a slotted groove 13 extending across the said table. At the other end of the table three similar clamps 14 are provided but these are capable of longitudinal movement and are guided in longitudinal guides 15. The clamps consist essentially of a member 16 having a slot 17 to accommodate the end of the strip 3 and an eccentrically mounted grooved roller 18 in contact with the said strip as shown in Figure 7. Each of the clamps 14 is connected to a ram 19 working in a double acting hydraulic cylinder 20 and all three rams are arranged to operate simultaneously.

When the rams are operated in the direction of arrow "B" the eccentrically mounted grooved rollers 18 tend to rotate in a clockwise direction (Figure 7) and consequently they grip the strip with increasing intensity as the pull is increased. It is found that a tension of about two tons can be applied to the strip without any tendency for the latter to slip. When the strip is required to be released it is only necessary to operate the hydraulic rams in the opposite direction. This movement causes the grooved rollers 18 to rotate slightly in an anti-clockwise direction and the grip is thereby automatically released. The travel of the rams is about four feet so that strips varying in length by this amount can readily be treated. Where strips of shorter length are required to be surfaced, the clamps 12 are removed from the slotted groove 13 and are transferred to a further slotted groove 21.

A travelling carriage 22 is adapted to move along the whole length of the table and is mounted as shown in Figure 5 on four wheels 23 positioned at each corner of the carriage. These wheels, which are arranged out of contact with the strips 3, run on two inlaid flat steel rails 24 (Figure 3) which extend the whole length of the table, the carriage being prevented from leaving the rails by four vertical rollers 25 which contact with the sides 26 of the table 1. At one end of the carriage two vertical tool posts 27 are arranged to slide within rectangular guides formed in the body of

the carriage. Each tool post forms the holding means for a cutting tool 28 and a roller 29, the whole tool post assembly being pressed in a downward direction by means of a spring 30 interposed between the upper face 31 of the said post and a yoke piece 32 which is affixed to the body of the carriage. Both rollers are adapted to ride over the surface of the strip 3 and the downward pressure on the tool posts can be adjusted by means of adjusting screws 33 on the yoke pieces 32. The carriage, which is preferably constructed of cast steel, is made sufficiently heavy to ensure that the pressure exerted on the rollers 29 does not lift the carriage as a whole.

The thickness of material removed from the surface of the strip is determined by the vertical position of the cutting tool 28 relative to the roller 29 and the necessary adjustment of the tool to within very fine limits is obtained by means of an extended spindle 34 attached to the said tool, the upper end of the spindle being screwed with a fine thread which is adapted to co-operate with an adjusting nut 35 as shown in Figure 6. After adjustment, the tool is firmly positioned in its holder by means of a sliding wedge 36 which is drawn up into the locking position by means of an off-set extended tubular portion 37, co-axial with the spindle 34 which is screwed externally at its upper end to co-operate with a screwed collar 38, the latter being adapted to bear on the upper face 31 of the tool post 27. The adjusting nut 35 which is free to turn in a recess formed at the top of the collar 38 is provided with a marked disc 39 which, in conjunction with a fixed pointer 40, serves to indicate the depth of cut. The tools are set obliquely as shown so that the metal shavings are deflected away from the rollers, the said tools being arranged substantially on the vertical centre line of the rollers and the cutting angle or angle of rake 40 of the tool is preferably about 8°.

The carriage is traversed along the whole length of the strip by means of a wire rope 41 which is wound round a winch drum 42, the latter being driven by an electric motor 43 through a reduction gear 44. The ends of the rope 41 are firmly secured to the carriage at 45 and the rope passes round pulleys 46 and 47 located at each end of the table. The pulley 47 is mounted on slideable bearings 48 which are coupled to a tensioning gear 49 so that the tension in the rope can be readily adjusted. The whole of the driving mechanism is housed within a pit located beneath the table as shown in Figure 1. The extent of the travel of the carriage is governed by automatic limit switches (not shown on the drawings) associated with the driving motor circuit.

The rails 24, upon which the carriage rides, are upwardly inclined by a small amount at the end 50 of the table so that the carriage is slightly elevated at the end of its travel to ensure that on the forward stroke the cut is applied gradually and without shock. Auxiliary rollers 51 are provided at the front end of the carriage and serve to lift the latter clear of any uprising portions or obstructions in the strip which might otherwise foul the front portion of the carriage.

During the backward travel of the carriage the latter is slightly elevated so that the tools and the rollers are lifted completely clear of the strip. This is accomplished by providing a further set of rollers 52 which are adapted to engage with runners 53 formed in the side of the table. These runners are inclined in a downward direction at each end of the table as indicated at 54 and 55.

The rollers 52 are carried on the arms 56 which are pivoted in the manner shown in Figure 4. (The carriage in Figure 4 is shown at the end of the table remote from the end indicated in Figure 1.) During the forward or cutting stroke the rollers trail along the runners as shown in full lines in Figure 4 and the weight of the carriage is carried by the wheels 23 which ride on the rails 24.

- 10 When the carriage reaches the end of its stroke the rollers 52 ride down the inclined runners at 55 and the arms 56 swing by gravity into a vertical position. Further movement of the arms in an anti-clockwise direction is prevented, so 15 that when the carriage is moved in the left hand direction on its return travel, the rollers 52 ride up the inclined runners at 55 and the arms assume the position shown in dotted lines in Figure 4, thus raising the carriage as a whole. The 20 downward movement of the tool posts in their guides is limited by suitable stops, not shown in the drawings, and the carriage is lifted by an amount which ensures that the tools are raised completely clear of the strip. At the end of the 25 return travel the rollers 52 ride down the portion of the side runners at 54 to lower the carriage once again on to the rollers 23.

As the tool posts are capable of vertical movement, the rollers, together with their attendant 30 tools, follow surface contour of the strip so that the thickness of metal removed is substantially uniform throughout the length of travel of the carriage and the effect of irregularities in the contour of the strip across its width is automatically compensated for by the fact that the tools are capable of independent movement. In order 35 to treat the whole surface of the strip, the latter is moved laterally on the table by means of simple hand levers after the tension in the strip has been 40 released by operating the hydraulic rams 19 in the direction of arrow "C". The amount by which the strip is moved over is slightly less than the width of the tool and the correct position of the strip is gauged by parallel guide lines marked 45 on the surface of the table at each end as indicated at 57 in Figure 7. The strip is again tensioned after repositioning, two or three clamps being adapted to grip the strip, and after the first cut has been made, one of the tools is 50 adjusted by an amount substantially equal to the thickness of the initial cut since the roller adjacent to this tool lies within the groove formed by the first cutting operation. No further adjustment of this tool is required but before the 55 last cut is made the roller of the other tool will ride on a treated portion of the strip and consequently a similar adjustment to this tool is necessary.

The disposition of the tool posts is such that 60 the carriage can ride over the whole of the strip without fouling the clamps 12 and 14 or the hydraulic rams. To prevent any tendency for the central portion of the strip to move laterally on the table, suitable side stops may be provided 65 which contact with the sides of the said strip. A V shaped brush 58 is positioned on the underside of the carriage for the purpose of removing any swarf lying on the surface of the strip, means (not shown on the drawings) being provided for 70 removing small pieces of swarf adhering to the bristles of the brush. Alternatively, a smooth deflecting member composed of rubberized canvas or the like may be used instead of a brush for removing the swarf.

75 After one side of the strip has been completely

surfaced, the strip is turned over and the opposite side is treated in the manner described. This may be carried out on the same machine or the strip may be conveyed along the roller table 59 for surfacing on a second machine of similar 5 design.

In an alternative form of machine as shown in Figures 8 to 10 the cutting tools 60 are mounted in a fixed carriage or housing 61 and the strip 62, which is introduced into the machine in the form 10 of coils, is moved relative to the tools. The untreated strip, which is uncoiled on a decoiler 63, is passed through a pair of driven pinch rolls 64 and is flattened out by a set of flattening rolls 65. After passing through a further pair of pinch 15 rolls 66 the strip is introduced to the cutting tools and after surface treatment is passed through a final pair of rolls 67 before being wound round a tension coiler 68. This coiler, which is provided 20 with suitable gripping means for tightly gripping the end of the strip, pulls the strip past the cutting tools and is driven by an electric motor 69 through a reduction gear 70.

Ten cutting tools are provided which are mounted in slideable tool posts 71 arranged in 25 staggered formation as shown in Figure 9 so that the whole width of the strip is surfaced in one operation. The arrangement of the tool posts and manner in which the cutting tools are adjusted and locked in position is substantially the 30 same as in the machine previously described. Each cutting tool 60 has a roller 72 mounted adjacent thereto which bears against two backing rollers 73, the latter being journaled in bearings 74. The whole roller assembly is located in 35 position by means of a cover plate 75 which is screwed to the tool post by screws 76 as shown in Figure 10.

The tool posts 71 are pressed in a downward direction by means of springs 77 interposed between a triangular shaped plate 78 and the upper face of each tool post. The plate 78 is hinged at 79 and is adapted to be downwardly pressed at the free end by turning a large nut 80 mounted on a screwed spindle 81. In this manner the 45 pressure on the tools is applied progressively and gradually so that shock is eliminated, and excessive tension in the strip is avoided at the commencement of the cutting operation. After 50 the whole of the surface of the strip has been treated, the coil is removed from the tension coiler 68, which is of the usual contracting drum type, and the opposite side of the strip is then treated in the manner described.

According to the form of the invention illustrated in Figs. 11 to 15 the apparatus comprises 55 a rigidly supported metal table 101 about four feet wide and seventy feet long which carries a traveling carriage 102 adapted to move along the whole length of the table. A strip of hot rolled 60 brass 103 about two feet wide by one tenth of an inch thick and about sixty feet long, the surface of which is required to be prepared, is placed on top of the table and is firmly secured to same at each end by means of clamps 104. The traveling 65 carriage 102 is mounted on two sets of rollers 105 and 106 located at the front and rear of the carriage frame and is arranged to ride on top of the brass strip 103 with the rollers in contact with the upper surface of the said strip as shown 70 in Figures 11, 12 and 13.

Two sets of cutting or scraping tools 107 are attached to the carriage and these are located in suitable tool holders 108 on either side of the rear rollers 106. The tools and holders are ar- 75

ranged so that the cutting edges of the said tools lie substantially on the center line of the rollers and the edges are ground at an oblique angle, as shown in Figures 12 and 14 so that the metal shavings are deflected away from the rollers. 5 Adjusting screws 109 are provided for regulating the depth of cut and tool clamping bolts 110 and 111 serve to secure the tools firmly in position in the holders.

10 The carriage 102 is heavily loaded, preferably by means of a dead weight, so that a distribution of forces ensuring the best conditions for cutting is obtained. Means are provided for traversing the carriage along the whole length of the strip and this preferably takes the form of an endless 15 rope 112 mounted on pulleys 113 located at each end of the table and driven by means of a winch 114 which is coupled to an electric motor 115 through a suitable reduction gear 116. Alternatively, the carriage may be traversed along the 20 length of the strip by means of an electric motor mounted on the carriage which drives, through suitable gearing, a pinion engaging with a rack affixed to the table, the gearing being arranged 25 so as not to interfere with the small up and down movement of the carriage. When the carriage is moved forward for the working stroke the cutters 107 engage with the strip 103 and are set so as to remove a shaving of metal about one and a half thousandths of an inch in thickness. The thickness 30 of the metal removed is maintained substantially uniform throughout the length of the travel since the tools which are mounted on the carriage follow the surface contour of the strip.

35 In order to prevent the wear of the tools during the backward travel of the carriage, the latter is arranged to be lifted completely clear of the metal strip by means of a further set of rollers 117 mounted in suitable bearings on the side 40 frames of the carriage, said rollers being adapted to ride on elevated rails 118 attached to the side frames 119 of the table 101. The arrangement is such that the rollers 117 are out of contact with the rails during the working travel of the carriage, as shown in the drawings, but come into 45 operation to lift the carriage clear of the strip on the backward travel by moving the hand lever 120, at the end of the working stroke, into the position shown in chain dotted lines in Figure 12.

50 The movement of the hand lever into this position moves the rollers 117 laterally until they assume a position immediately above the rails which are downwardly inclined at each end, as indicated at 121 in Figure 11, in order to permit of this lateral movement. If desired, instead of moving the rollers 117 by hand, these may be moved over automatically when the carriage reaches the end of its travel. Other means, not 55 shown in the drawings, may be provided for lifting the tools clear of the work during the return stroke so as to enable a second set of tools to come into operation during that stroke, thus making the device double acting.

60 In order that the whole surface of the strip 103 may be prepared, the said strip is moved laterally across the table by mounting the clamps 104 on square threaded spindles 123 which are turned by means of handles 124. Instead of turning the spindles by hand, these may be motor driven and 65 automatically operated when the carriage reaches the end of its travel.

65 In an alternative arrangement, not shown on the drawings, the holders for the tools may be fitted to an automatic cross traversing device 70 whereby the tools are moved in progressive steps

across the width of the strip, and in this case the strip is rigidly clamped to the table.

Machines constructed in accordance with my invention may be operated at high speeds, cutting speeds up to three hundred feet per minute 5 being possible with certain kinds of material. It will be understood that my invention is not limited to the type of cutting tools described since these may, if desired, be replaced by rotary cutters or rotary grinding wheels.

10 As many variations may be made in the present invention, it is to be understood that I do not desire to be limited by the foregoing description and illustration except insofar as is indicated in the appended claims.

15 I claim:

1. Apparatus for treating the surface of a material, particularly a non-plane undulating strip material, comprising means for supporting the said material, a tool capable of movement toward 20 and away from the surface of the material being treated for removing from said material a surface layer of small thickness, means for causing the said tool and the material to move longitudinally in cooperating relationship relative to 25 each other, resilient means for pressing the tool against the surface of the material being treated, and means rigidly mounted relative to the tool and arranged to contact with the undulating surface of said material solely at a point abreast 30 of and substantially in alignment with the cutting edge of said tool for solely controlling the position of the said tool relative to the said supporting means in accordance with the contour 35 of the surface being treated.

2. Apparatus as claimed in claim 1 in which the controlling means comprises a roller rigidly mounted with regard to the tool, the roller and the tool together being capable of up and down movement relative to the supporting means and both being capable of moving longitudinally in co-operating relationship with the surface being treated.

3. Apparatus as claimed in claim 1 in which the controlling means comprises a roller rigidly mounted with regard to the tool, the cutting edge 45 of said tool being positioned substantially on the center line of said roller.

4. Apparatus as claimed in claim 1 comprising a plurality of tools located at an oblique angle in order to disperse the material removed 50 from the surface layer.

5. Apparatus for treating lengths of a material having an undulating surface lying substantially in one plane and of which the magnitude of the undulations is very small in relationship to the surface area undergoing treatment, comprising a supporting base plate for the said material, a carriage traveling longitudinally over the surface of said material, a tool for removing a surface layer of small thickness from said material mounted on the carriage for up and down movement relative to the carriage and base plate, a roller contacting the surface of the material at a point abreast of and substantially in alignment 65 with the cutting edge of the tool, said roller being rigidly mounted relative to the tool so as to be movable up and down with it as aforesaid; and resilient means for maintaining the tool and roller in engagement with the surface of the 70 material.

6. Apparatus as claimed in claim 5 in which means are provided on the baseplate for supporting the carriage during its movement in a forward direction and other means are provided 75

for supporting the carriage at a higher level on its return movement so that the tool is raised out of engagement with the surface.

7. Apparatus for treating lengths of a material having an undulating surface lying substantially in one plane and of which the magnitude of the undulations is very small in relationship to the surface area undergoing treatment, comprising a supporting base plate for the said material, a weighted carriage capable of traveling on supports contacting with the surface of the said material, means for causing the weighted carriage to travel longitudinally over the surface of the said material, and at least one stationary tool mounted rigidly with respect to the carriage and adapted to remove from said material a surface layer of small thickness, the said tool being arranged to contact with the surface of the said material at a point abreast of and substantially in alignment with the point of contact of at least one of said carriage-supports with the said surface so that the said support controls the position of the tool relative to the base-plate in accordance with the contour of the surface being treated.

8. Apparatus for treating the surface of a non-plane strip material comprising a fixed carriage holding at least one knife movably mounted on said carriage for removing from said material a surface layer of small thickness, means for causing the strip material to move longitudinally relative to the carriage and in co-operating relationship with the knife, at least one roller rigidly mounted with respect to the knife for controlling the position of said knife relative to the surface of the material in accordance with the contour of said surface, said knife and roller contacting said surface in a line extending substantially transversely to the line of travel of said strip material, and resilient means for maintaining the knife and the roller in engagement with the surface of the material during the longitudinal movement thereof.

9. Apparatus as claimed in claim 8 comprising a plurality of knives and a plurality of rollers arranged in staggered formation.

10. Apparatus as claimed in claim 8 comprising means for bringing the knife into co-operating relationship with the surface of the material slowly and gradually at the commencement of the operation.

11. Apparatus as set out in claim 7 the means for causing longitudinal movement of said carriage permitting movement of said carriage toward and away from said baseplate.

12. Apparatus as set out in claim 7 including a flexible cable in the means for causing longitudinal movement of said carriage.

13. In a machine of the character described, a work supporting table, a weighted carriage supported by and travelling along said table, a tool holder slidably mounted on said carriage

for movement toward and away from said work, a tool carried by said tool holder, a roller carried by said tool holder for controlling the position of said tool relative to said table in accordance with the contour of said work, said tool and roller contacting said work in a line extending substantially transversely to the line of travel of said tool, and resilient means for urging said tool holder and the tool and roller carried thereby toward said work.

14. A machine as set out in claim 13 including means for adjusting the position of the tool relative to said roller to adjust the depth of cut of said tool.

15. Apparatus as set out in claim 1 including a set of rollers which normally support the carriage during movement in a forward direction and a second set of rollers which automatically raise and support the carriage at a higher level on its return movement so that the tool is raised out of contact with the surface of the material.

16. Apparatus for treating the surface of a non-plane strip material comprising a supporting base plate for the said material, a weighted carriage having front and rear rollers supporting it in contact with the surface of said material, means for causing the weighted carriage to travel longitudinally over said surface, and at least one stationary tool mounted rigidly with respect to the carriage and adapted to remove from said material a surface layer of small thickness, the said tool being arranged to contact with the surface of the said material at a point abreast of and substantially in alignment with the point of contact with said surface of a rear roller so that the said rear roller controls the position of the tool relative to the base plate in accordance with the contour of the surface being treated.

17. Apparatus for treating lengths of a material having an undulating surface lying substantially in one plane and of which the magnitude of the undulations is very small in relationship to the surface area undergoing treatment, the said apparatus comprising means for supporting the said material, a tool for removing from said material a surface layer of small thickness and capable of movement toward and away from said supporting means, means for causing the tool and the material to move longitudinally in cooperating relationship relative to each other, resilient means for maintaining the tool in engagement with the surface of the material during said relative movement, and means rigidly mounted relative to the tool and arranged to contact with the undulating surface of said material at a point abreast of and substantially in alignment with the cutting edge of said tool for controlling the position of said tool relative to said supporting means in accordance with the contour of the surface being treated.

JOHN EDWIN MALAM.
